METHOD AND APPARATUS FOR RECOILING
METAL COILS

Agnes J. Reeves Greer, Morgantown, W. Va.

Application March 10, 1939, Serial No. 261,038

9 Claims. (Cl. 242—78)

The invention relates to a method of and apparatus for forming coils of metal preparatory to pickling the coils in a pickling machine of the general type disclosed in my prior Patent No. 2,091,921, issued August 31, 1937, Shoemaker Patent No. 2,120,843, issued June 14, 1938, and my co-pending application Serial No. 249,484, filed January 5, 1939; and this application is an improvement upon my co-pending application for Recoiler for metal coils, Serial No. 230,304, filed September 16, 1938.

The general type of pickling machines above referred to provide means for supporting the metal coils upon mandrels which are rotated as they are progressed through the pickling and washing tanks, whereby the coils are rotated upon the mandrels as they are carried through the pickling and washing solutions.

It is necessary that the convolutions of the coil be opened up, or separated, before entering the pickling machine, so that none of the convolutions will remain in contact with each other while in the pickling solution, as otherwise the pickled metal will be marred by black spots or marks where the acid has not had access to the surface of the metal.

To this end the Shoemaker patent contemplated the use of a back spinner located between the recoiler and the pickling tank for opening up or separating the convolutions of each coil before it is charged into the pickling tank.

My co-pending application Serial No. 230,304 dispensed with this back spinner and provided for back spinning the coil upon the recoiler, so as to open up the convolutions of the coil prior to the pickling operation.

In my co-pending application Serial No. 249,484, means are provided for further back spinning of the coils as they are passed through the solution, by rotating the mandrels, on which the coils are supported, in a reverse direction during at least a part of the time.

In all of the above cases the coil was formed in a conventional spiral, comprising a continuous curve from the center to the outside of the coil. This frequently resulted in two convolutions of the coil contacting with each other for some distance while the coil was in the pickling solution, thus, preventing the acid from properly contacting the opposed surfaces of these convolutions of the coil and resulting in an improperly pickled coil having black spots upon the surfaces thus not properly exposed to the action of the acid.

The present application contemplates the formation of a coil which will prevent any of the

convolutions of the coil from remaining in contact with each other during the time the coil is passing through the pickling solution.

The object of the invention is to provide a novel method for forming a metal coil of such shape that none of the convolutions of the coil will remain in contact with each other.

Another object is to provide means for forming a metal coil of such shape that the convolutions of the coil will not contact with each other.

A further object is to provide for the formation of a metal coil in which each convolution of the coil has a plurality of angular bends therein.

A still further object is the provision of such a coil in which the angular bends are irregularly spaced around each convolution of the coil.

Another object is the provision of means for forming such a coil and then back spinning the coil to separate or open up the convolutions so that the angular bends of adjacent convolutions will not register with each other.

A still further object of the invention is the provision of a drum upon which the coils are formed, said drum having longitudinally disposed ribs around its exterior for forming angular bends in the convolutions of the metal coil as it is coiled upon the drum.

The above objects together with others which will be apparent from the drawings and following description or which may be later referred to may be attained by constructing the recoiler mechanism and forming the improved metal coil in the manner illustrated in the accompanying drawings in which

Figure 1 is an elevation of a recoiler drum showing a metal coil wound thereon;

Fig. 2, a view similar to Figure 1 showing the metal coil after it has been back spun on the drum to separate or open up the convolutions of the coil;

Fig. 3, an elevation of a coil formed in accordance with the invention suspended on a mandrel for passing through a pickling machine; and

Fig. 4, a plan view of a recoiler drum for forming the improved coil.

Similar numerals refer to similar parts throughout the several views.

The hot rolled coil to be recoiled for pickling in accordance with the present invention, is uncoiled and may be fed to the improved recoiler by means of a feeding mechanism including feed rolls, edge rolls, pinch rolls, brake mechanism, leveling rolls, and the like, as illustrated and described in detail in my co-pending application Serial No. 230,304, a portion of this mech-

cent convolutions are continuously shifting their positions.

With this formation of coil it has been found in actual experience that the coils are perfectly pickled when passed through the pickling machine in the manner above referred to and the angular bends formed in the convolutions of the coil do not in any way interfere with the proper cold rolling of the pickled metal.

10 According to the provisions of the patent statutes I have explained the principle of my invention and described one embodiment thereof, but I desire to have it understood that within the scope of the appended claims the invention may 15 be practiced otherwise than as specifically illustrated and described.

I claim:

1. The method of forming a coil of metal which consists in winding the metal spirally upon itself

20 in one direction to form a coil each convolution of which has a plurality of spaced angular bends therein and then separating the convolutions of the coil so that the angular bends of adjacent convolutions will be spaced from each other.

25 2. The method of forming a coil of metal which consists in winding the metal spirally upon itself in one direction to form a coil each convolution of which has a plurality of irregularly spaced angular bends therein and then separating the 30 convolutions of the coil so that the angular bends of adjacent convolutions will be spaced from each other.

3. The method of forming a coil of metal which consists in winding the metal spirally upon itself

35 in one direction to form a coil each convolution of which has a plurality of spaced angular bends therein and then holding the outer end of the coil against movement and positively rotating the inner end of the coil in the opposite direction

40 to separate the convolutions of the coil.

4. The method of forming a coil of metal which consists in winding the metal spirally upon itself in one direction to form a coil each convolution of which has a plurality of irregularly spaced

45 angular bends therein and then holding the outer end of the coil against movement and positively rotating the inner end of the coil in the opposite direction to separate the convolutions of the coil.

5. A recoiler for recoiling a coil of metal and

50 separating the convolutions of the coil comprising a drum, spaced ribs upon the exterior of the drum, means upon the drum for connecting one end of a metal coil, means for rotating the drum in one direction for coiling the metal thereon to

55 form a coil the convolutions of which have spaced, angular bends therein, a stop adjacent to the drum for engaging and holding the outer end

of the coil against movement, and means for rotating the drum in the opposite direction to separate the convolutions of the coil so that the angular bends of adjacent convolutions will be spaced from each other.

6. A recoiler for recoiling a coil of metal and separating the convolutions of the coil comprising a drum, irregularly spaced ribs upon the exterior of the drum, means upon the drum for connecting one end of a metal coil, means for rotating the drum in one direction for coiling the metal thereon to form a coil the convolutions of which have spaced, angular bends therein, a stop adjacent to the drum for engaging and holding the outer end of the coil against movement, and means for rotating the drum in the opposite direction to separate the convolutions of the coil so that the angular bends of adjacent convolutions will be spaced from each other.

7. A recoiler for recoiling a coil of metal and 20 separating the convolutions of the coil comprising a drum, spaced, longitudinally disposed ribs upon the exterior of the drum, means upon the drum for connecting one end of a metal coil, means for rotating the drum in one direction for 25 coiling the metal thereon to form a coil the convolutions of which have spaced, angular bends therein, a stop adjacent to the drum for engaging and holding the outer end of the coil against movement, and means for rotating the drum in 30 the opposite direction to separate the convolutions of the coil so that the angular bends of adjacent convolutions will be spaced from each other.

8. A recoiler for recoiling a coil of metal and 35 separating the convolutions of the coil comprising a drum, irregularly spaced, longitudinally disposed ribs upon the exterior of the drum, means upon the drum for connecting one end of a metal coil, means for rotating the drum in one 40 direction for coiling the metal thereon to form a coil the convolutions of which have spaced, angular bends therein, a stop adjacent to the drum for engaging and holding the outer end of the coil against movement, and means for rotating 45 the drum in the opposite direction to separate the convolutions of the coil so that the angular bends of adjacent convolutions will be spaced from each other.

9. The method of forming a coil of metal which 50 consists in winding the metal spirally upon itself in one direction to form a coil, the metal being so wound that bends are formed therein, and then partially unwinding the coil to separate the convolutions thereof so that the bends in adjacent convolutions will be spaced from each other.

PROCESS FOR ACTUATING CATALYTIC SURFACES

Marion H. Gwynn, Leonia, N. J.

No Drawing. Application December 24, 1936,
Serial No. 117,515

9 Claims. (Cl. 23—233)

This invention relates to catalysts and to the preparation and reactivation of active catalytic surfaces or surface layers, particularly those which comprise a secondarily ferromagnetic metal and which are adherent or fixed to the underlying metal. These treated surfaces or surface layers may be used in hydrofining, i. e., hydrogenating and/or refining oils and other carbonaceous compounds, particularly in sulphur sensitive hydrofining. These surface layers, especially in conjunction with a promoter for dehydration, are extraordinarily catalytic for the conversion of water gas to light hydrocarbons and like compounds. The treated surface layers may also be used as reagents, as for example in the formation of metallic sulphides or carbonyls, or as adsorption or purifying agents, as in the treatment of vegetable or animal glycerides before steam deodorization, or as when doctor sweetening light petroleum or like distillates; or as tower packing or otherwise.

The use of hypochlorite solutions on metals, together with a subsequent reduction in hydrogen, has been proposed to produce catalysts which are then used in the hydrogenation of oils. However, on metals like cobalt the proposed method fails entirely to produce a catalyst, and on nickel fails to prepare highly active and adherent catalytic surfaces, and fails to prepare any catalyst which maintains its activity substantially uniform during hydrofining.

The preferred form of my invention relates to the preparation of highly active hydrated and black fixed catalytic surfaces or surface layers by preliminarily treating a metal such as cobalt or nickel in a foraminous state to form an adherent surface layer which is moderately catalytic with or without gentle roasting, being also preferably hydrated. The surface comprising the treated surface layer is then oxidized until highly catalytic with an aqueous hypobromite solution containing a high and sufficient concentration of alkali to repress the formation of free hypobromous acid, but insufficient to exert a solvent action on the surface layer. The catalyst produced in this way without further chemical treatment is ready for use in hydrofining operations and maintains its activity substantially uniform during hydrofining until spent. Instead of starting with a new metal surface or with a surface comprising a readily oxidizable compound of the catalytic metal I may start with surfaces which have been used in hydrogenation and which must be reactivated. When my invention is used to reactivate catalyst surfaces containing sulphur,

I find the alkaline earth hydroxides useful to produce alkaline solutions of the hypohalite compounds, as the sulphur is removed by forming insoluble sulfate precipitates.

According to my invention instead of using a hypobromite solution I can use other hypohalites in alkaline solution, particularly the more stable forms of hypohalites to produce catalysts, and these catalysts are usable as such without requiring further chemical treatment before use. 5 It is known that hypohalite compounds decompose readily but that they have different degrees of stability. The more labile forms are useful in initiating oxidation of the catalyst surface, but once the oxidation is begun the more stable forms 10 of hypohalite compounds oxidize the surface more uniformly and efficiently, and yield the more adherent surfaces. Of the several hypohalites, the more adherent surfaces. Of the several hypobromites are generally the most stable. Mixing 15 hypohalites of different halogens renders the hypohalites less stable. Dissolved catalytic metals also render hypohalite solutions less stable. Decreases of temperature and of concentration 20 of hypohalites are stabilizing factors. Free hypohalous acids are less stable than other characteristic hypohalite forms and should be avoided particularly in the liquid phase since they exert 25 a detrimental solvent action on the surface layer. Alkali added to aqueous hypohalite salt solutions 30 inhibits the hydrolysis of the salt to free hypohalous acid. Hence a large excess of alkali or hydroxyl ion of at least one molar concentration 35 per molar concentration of hypohalite salt is a stabilizing factor, exerting a substantial repressive effect on the hydrolysis of the hypohalite salt. A highly alkaline hypohalite solution may increase in stability during activation of the metallic surfaces because the molar concentration 40 of hypohalite is decreasing by use, while the molar concentration of alkali remains relatively constant. For instance in Example 1 (to be set forth later on in the description) the molar concentration of sodium hydroxide relative to the molecular concentration of sodium hypobromite 45 exceeds unity in the fresh solution, but the relative concentration of sodium hydroxide increases during immersion of the cobalt surfaces. With proper treatment of the metal surface, I may use 50 the relatively stable forms of hypohalites.

The hypohalite solutions are used in an alkaline solution with the alkalinity so chosen as to eliminate essentially all solvent action of the hypohalite solutions on the surface layer. For 55 the optimum alkalinity in my hypohalite solu-
